US0D1021264S

(12) United States Design Patent (10) Patent No.: US D1,021,264 S
(45) Date of Patent: * Apr. 2, 2024

(54) LIPSTICK

(71) Applicant: ELC MANAGEMENT LLC, Melville, NY (US)

(72) Inventors: Yeon Jung Roh, New York, NY (US); Rory Gevis, New York, NY (US)

(73) Assignee: ELC MANAGEMENT LLC, Melville, NY (US)

() Term: 15 Years

(21) Appl. No.: 29/774,261

(22) Filed: Mar. 15, 2021

(51) LOC (14) Cl. 28-02

(52) U.S. Cl.

USPC D28/85

(58) Field of Classification Search

(57) CLAIM

The ornamental design for a lipstick, as shown and described.

DESCRIPTION

FIG. 1 is a top front isometric perspective view of a lipstick showing the claimed design;

FIG. 2 is a bottom rear isometric perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top perspective view of the liquid lipstick shown with cap removed in an open configuration;

FIG. 10 is a bottom rear perspective view thereof;

FIG. 11 is a front view thereof;

FIG. 12 is a rear view thereof;

FIG. 13 is a top view thereof; and,

FIG. 14 is a bottom view thereof.

The broken lines in the figures and unshaded areas within depict portions of the lipstick that form no part of the claimed design.

1 Claim, 10 Drawing Sheets
